UNITED STATES PATENT OFFICE.

CHARLES E. SPENCER, OF CHICAGO, AND ROBERT C. SPENCER, JR., OF RIVER FOREST, ILLINOIS.

CASEMENT-WINDOW ADJUSTER.

1,314,023.

Specification of Letters Patent. Patented Aug. 26, 1919.

Application filed January 8, 1917. Serial No. 141,138.

To all whom it may concern:

Be it known that we, CHARLES E. SPENCER and ROBERT C. SPENCER, Jr., citizens of the United States, residing at Chicago and River Forest, respectively, county of Cook, and State of Illinois, have invented certain new and useful Improvements in Casement-Window Adjusters, of which the following is a full, clear, concise, and exact description, reference being had to the accompanying drawings, forming a part of this specification.

Our invention relates to casement window adjusters and particularly to adjusters which are secured to the window sill or stool and have a mechanical connection with the inside face of the window sash.

It is one of the objects of the present invention to provide a casement window adjuster which is absolutely noiseless in its operations and one which can be very easily operated, that is, one having a minimum amount of friction. With this object in view we provide an operating lever arranged to be attached to the window frame or sill having an outwardly extending lever or arm mechanically connected with the window sash. To produce the easy operating qualities of the adjuster and the anti-friction operating means we provide an anti-friction roller connection between the window frame and the operating lever or arm. We are aware of the fact that anti-friction roller means have been employed between an operating lever and a window frame in the past, but such constructions, so far as we are aware, have necessitated the use of specially designed window frames and window sashes, or they have necessitated drilling and similar work on the woodwork constituting the window frame or the window sash or both.

It is a further object of our invention to provide an easily operated anti-friction casement window adjuster which can be applied to the window and to the frame in such a way as to avoid the necessity of doing any special work on the woodwork constituting the frame and sash.

A further object of our invention is to provide in conjunction with the above an improved locking means for locking the window in any position to which it may be moved, the said locking means being operated solely by the same mechanism or han-

dle device for swinging the window to any one of its several positions.

These and other objects of our invention will be more clearly brought out in connection with the accompanying drawings, in which

Figure 1 is a fragmentary front elevational view of a casement window having the device of our invention mounted thereon, some of the parts being broken away in this figure to more clearly illustrate the construction of the adjuster;

Fig. 2 is a top view of Fig. 1 or a horizontal cross-sectional view of the window shown in Fig. 1;

Fig. 3 is a detail cross-sectional view of the anti-frictional connection between the operating lever and the window frame, this view being taken along the line 3—3 of Fig. 2, looking in the direction indicated by the arrows;

Fig. 4 is a detail view of a modified form of anti-friction connection between the operating lever and the casement window sash;

Fig. 5 is a perspective view of the guide member arranged to coöperate with the friction device illustrated in Figs. 2 and 4;

Fig. 6 is a view similar to Fig. 3 of a further modified form of anti-friction connection between the operating lever and the window sash;

Fig. 7 is a view similar to Fig. 2 showing the modified arrangement in which the guide 40 forms a part of the locking mechanism for locking the window in any one of its adjusted positions;

Fig. 8 is an enlarged fragmentary cross-sectional view taken along the line 8—8 of Fig. 7, looking in the direction indicated by the arrows; and

Fig. 9 is an enlarged detail cross-sectional view taken along the line 9—9 of Fig. 7, looking in the direction indicated by the arrows.

Similar characters of reference refer to similar parts throughout the several views.

In Figs. 1 and 2, 7 illustrates the window jamb, 8 the stool and 9 the sill. The casement window sash 10 is hinged as shown at 11 to the jamb 7, so as to swing outwardly as shown by the dotted lines in Fig. 2. The stool 8 has mounted thereon a base plate 12 to which is journaled for rotation a hub 13 having an outwardly extending arm or lever 14. To facilitate rotation of the hub 13

and thus movement of the lever 14 the hub 13 has an outwardly extending rod 15 to which is attached a sleeve 16. The sleeve 16 is mounted on the rod 15 so as to have 5 longitudinal movement relative to the rod, the sleeve being keyed to the rod in any suitable manner, so as to prevent angular movement of the sleeve relative to the rod. The lower side of the sleeve 16 carries a 10 tooth or projection 17 arranged to coöperate with any one of the several teeth 18 provided in the base 12. From the construction thus far described it will be observed that the arm 14 may be swung to 15 any position by pulling the sleeve 16 outwardly and releasing its projection 17 from the teeth 18, and swinging the handle 16 and thus the hub 13 together with the lever 14 to any position desired. To lock 20 the arm 14 in any position to which it may be moved the handle 16 is again moved inwardly to cause the projection 17 to coöperate and lock into one of the teeth 18. The specific construction thus far described 25 forms no part of the present invention and we have described it merely to aid in understanding the features which constitute our invention.

The outer end of the arm 14 carries a 30 rearwardly extending piece 19 which is rigidly attached to the arm 14. This piece 19 extends through a slot 20 provided in the guide member 21 shown in perspective in Fig. 5. The end of the piece 19 which projects into the guide member 21 as most clearly shown in Fig. 3 is provided with a steel pin 22 upon which are mounted two fiber rollers 23—23, the rollers being beveled toward the piece 19 as most clearly 35 illustrated in Fig. 3. The guide member 21 is preferably formed of sheet metal and is bent to provide the two guiding or roller engaging faces 24—24.

To facilitate the mounting of the guide 40 21 on the window sash, the guide is provided with the apertures shown at 25—25 for the reception of screws which extend through the guide and into the woodwork forming the window sash. To close the 45 ends of the guide the two blocks 26—26 are employed which are held in place by means of the pins shown at 27—27. The guide 21 as most clearly shown in Figs. 1 and 2 is secured to the inside face of the 50 window sash and the operating mechanism is mounted directly on the window stool, thereby avoiding any and all cutting, drilling or mutilation of any of the woodwork. On account of the anti-friction roller 55 connection between the operating lever 14 and the window frame an absolutely noiseless device and one which can be very easily operated is obtained. A further advantage of the construction is that the guide piece 60 65 21 or in fact any of the mechanism of the

adjuster can be decorated, painted or in any other way provided with an ornamental covering without danger of affecting smooth running connection between the operating lever and the window sash. Although we 70 have described the rollers 23—23 as being constructed of fiber, we desire to have it understood that these rollers may be constructed of steel, brass, or any other suitable material if desired. 75

In the modification shown in Fig. 4 we have shown four rollers mounted on a bracket 28 which is pivotally connected at 29 to the operating lever 14^a. In this construction exactly the same guide member 80 21^a is used as is used in the construction shown in Figs. 1 and 2, the insertion of the bracket 28 being accomplished by removal of one of the end blocks 26.

In Fig. 6 we have shown a modification in 85 which the operating lever 14^b carries an outwardly extending piece 19^b to which is journaled only one roller 23^b. The guideway 21^b in this construction has only one outwardly extending piece or roller engaging 90 face 24^b. A washer 31 is interposed between the roller 23^b and the member 19^b, so as to provide a space between the same. The piece 24^b of the guide 21^b has an inwardly extending ledge 32 against which 95 the underside of the roller 23^b may rest. The purpose of the ledge or shoulder 32 is to prevent any possible sagging of the outer end of the operating lever or arm 14^b.

It is to be observed that the mechanism 100 of our invention may be used either at the right hand side of the window frame or the left hand side and that the only work necessary to attach the device to any kind of a casement window is the insertion of 105 the two screws to hold the guide 21 in place on the window sash. The device when applied to a casement window is pleasing in appearance and thus avoids the objections inherent in the devices of the prior art. 110 To conceal the entire guide member 21 it is only necessary to countersink the guide into the woodwork of the window sash, but we find this unnecessary in view of the fact that the anti-friction or roller mechanism 115 is entirely concealed by the guide member.

The locking mechanism constituting a 120 part of our invention is illustrated in Figs. 7, 8 and 9. In this construction the guide member 40 is provided with a slot extending along its front side through which the piece 41 carried by the operating lever 42 extends. The inner end of the piece 41 has journaled thereon the two rollers shown at 43 and 44 in Fig. 8. The pin 45 which serves to journal the rollers 43 and 44 onto the piece 41 extends downwardly as shown at 46 to fit into any one of a plurality of apertures 47—47 provided in the lower wall of the guideway 40. A flat spring 48 is carried by 125 130

- the piece 41 and rests against the upper wall of the guide 40, the tendency of the spring being to move the piece 41 and thus the outer end of the lever 42 downwardly with the result that the projection 46 is normally held in one of the apertures 47. The inner end of the operating lever 42 is fixed to a hub 49 which is rotatably mounted on the stud 50, as most clearly shown in Fig. 9.
- 5 The stud 50 has its upper and lower ends tapering inwardly so that the hub 49 and thus the lever 42 is permitted to rock or oscillate about the stud 50 when it is desired to produce such oscillation. The hub 49 is 10 connected with an operating handle 51 which is attached to the hub at 52 in any suitable manner, so that the handle 51 may be swung inwardly out of the way when not in use.
- 15 20 In opening the window or closing it the handle 51 is grasped and slightly pushed downwardly with the result that the hub 49 is oscillated about the stud 50 and the outer end of the lever 42 lifted against the tension 25 of the spring 48. This movement releases the projection 46 from the aperture in which it has been seated and permits movement of the operating lever and thus the casement window to any desired position. After the 30 window has been adjusted to the position desired the handle 51 is released and the spring 48 caused to move the projection 46 again into one of the apertures 47. If the pin 46 does not immediately register with 35 one of the apertures the handle 51 may be given a slight movement either in one direction or another about the stud 50, so that the projection 46 will be projected into one of the apertures.
- 40 45 50 55 60 65 70 75 80 85 90 95 100 105 40 What we claim as new and desire to secure by Letters Patent of the United States, is:
1. In a casement window adjuster the combination of an operating lever, means for pivoting the said lever to the frame of a casement window so that the lever may swing horizontally and rock vertically, and a tubular guide adapted to be attached to the sash of a casement window and arranged to receive the outer end of said operating lever, said guide being arranged to co-operate with the operating lever to lock the same against horizontal movement about the said pivot.
  2. In a casement window adjuster the provision of an operating lever arranged to be pivoted to the frame of a casement window, so as to swing horizontally and rock vertically, a square tubular guide provided with a slot in its front wall arranged to be attached to a casement window sash, the outer end of said operating lever extending through the slot in the guide and being provided with a roller on the inside of the guide, said guide having one of its walls provided with a plurality of locking sockets, a projection carried at the outer end of the lever arranged to fit into one of said sockets to lock the lever against horizontal movement, and spring means tending to move the projection into one of said sockets.
3. In a casement window adjuster the provision of an operating lever arranged to be pivoted to the frame of a casement window, so as to swing horizontally and rock vertically, a square tubular guide provided with a slot in its front wall arranged to be attached to a casement window sash, the outer end of said operating lever extending through the slot in the guide and being provided with a roller on the inside of the guide, said guide having one of its walls provided with a plurality of locking sockets, a projection carried at the outer end of the lever arranged to fit into one of said sockets to lock the lever against horizontal movement, and spring means carried at the outer end of the operating lever and within the guide for moving the outer end of the lever and thus the projection in a direction toward one of the sockets to effect locking of the lever against horizontal movement.
4. Means for adjusting a casement window comprising a slotted tubular guide adapted to be attached to the sash of the window, a lever having one end extending through said slot and provided with a roller engaging opposite sides of said guide, means for pivoting the other end of said window to the window frame, and means for locking and releasing said lever comprising a handle mounted on said lever and movable relatively to said pivoting means.
- In witness whereof, we hereunto subscribe our names this 20th day of December, A. D. 1916:
- CHARLES E. SPENCER.
